FIG. 2.

UNITED STATES PATENT OFFICE.

CHARLES G. ROBINSON, OF LEWISTOWN, PENNSYLVANIA.

APPARATUS FOR MOLDING.

1,146,736.

Specification of Letters Patent. Patented July 13, 1915.

Application filed April 2, 1912. Serial No. 687,976.

To all whom it may concern:

Be it known that I, CHARLES G. ROBINSON, a citizen of the United States, residing at Lewistown, in the county of Mifflin and 5 State of Pennsylvania, have invented a new and useful Improvement in Apparatus for Molding, of which improvement the following is a specification.

My invention relates to improvements in 10 the art of molding and in apparatus applicable thereto.

The invention is particularly applicable to the molding of truck and body bolsters; it is, however, applicable to the production 15 of all classes of castings.

The object of my invention is to produce a method and apparatus applicable to the production of castings and particularly to the production of truck and body bolsters, 20 whereby time and labor are minimized and large tonnage produced, and to this purpose my invention consists in the novel steps and operations hereinafter set forth.

In carrying out or practising my improved method I use the apparatus herein-after more specifically described, reference being had to the accompanying drawings forming part hereof, in which—

Figure 1 is a plan view of a portion of 30 my improved apparatus. Fig. 2 is an enlarged detail of one of the parts thereof. Fig. 3 is a side elevation of the apparatus.

In carrying out the method the cope 1 and drag 2 of the flask used are placed upon 35 a match plate 3 on which the pattern 4 has been secured. The flask is preferably hinged, *i. e.* the cope is hinged to the drag. Placing the cope and drag on the match plate upon which the pattern is secured enables the 40 ramming of the mold at one operation.

The method may be described as consisting of the following distinct steps or operations: First, placing on the match plate the hinged flask, *i. e.* the cope 1 and drag 2 which are 45 supported on the stationary support which in this form of apparatus comprises a bar or plate 6—6 arranged on each side of the frame 7 longitudinally thereof, the match plate being wider than the frame. The 50 match plate with the flask thereon is carried forward by the endless conveyer 8 until the same is brought to the ramming device 9 which is in direct alinement with the sand bin 10 from which the required amount of 55 sand is automatically dumped or fed into the

flask. It is immaterial what kind of sand is used but I prefer to grind all the sand used in this apparatus. After the flask has been rammed and thoroughly tamped by the ramming machine and bumped, a bottom 60 plate 11 is put on the drag half of the flask and securely bolted thereon. Any usual jarring machine may be used. After the mold has been rammed and bumped as hereinbefore described, it is carried forward to 65 the device 12, which reverses the flask, *i. e.* reverses the match plate so as to bring it to the upper side of the flask. The reversing mechanism employed consists of a receptacle 13 having compartments 14—15 longitudinally thereof in each side, the said receptacle being mounted upon a centrally disposed shaft 16, whereby when the flask is inserted in one of said compartments as shown in Fig. 3 and the shaft rotated automatically or manually, the flask is reversed, *i. e.* turned upside down. After this operation the flask is removed from the compartment of said receptacle and carried by the 70 conveyer toward and upon the table of the stripping machine 17. This machine automatically takes hold of the match plate and attaches to opposite corners thereof a vibrator whereby the match plate and patterns 75 secured thereon are removed from the mold, air being used to accomplish this operation. After the withdrawal of the patterns we have a complete mold which by the action of the conveyer is carried forward, the match plate being suspended in the stripping machine as shown in Fig. 3. The mold is carried forward to the conventional form of finishing table (not shown) where the cores are inserted and any necessary hand work performed, after which the flask is 80 carried forward, the cope half thereof having rollers 18 which engage upon the inclines 19 and cause the same to swing on its hinged connection as the drag half of the flask is being carried forward horizontally 85 as shown in Fig. 2.

The cope rides on the rollers thereof until it arrives at the apex of the incline, in so doing engaging against a guide or stop trigger 20 which being forced forward causes 90 the roller to travel up through the guide 21 until it arrives into the vertical passage therein upon which the trigger is returned to its normal position. The continued forward movement of the drag then causes the 95 100 105 110

complete reversal of the cope portion of the flask thereby closing the same, after which the cope and drag are bolted in the usual manner and are in position for pouring which may be performed at this point of the operation or the flask may be removed to a pouring floor.

The conveyer is provided with dogs 35 which engage the rear edge of the match 10 plate or flask whereby the same is moved forward.

In practising my invention, I preferably permit the casting to remain in the drag until cooled as this not only prevents the 15 casting from becoming crooked while cooling, but also takes care of shrinkage.

The advantages of my invention and its capacity to produce large tonnage in a minimum of time will be obvious to those skilled 20 in the art.

The conveyer may either have a continuous or an intermittent movement, according to the skill of the operators, and with the present construction the different operations 25 would be manually performed, although it would be entirely within the scope of the invention to provide automatic means for actuating the different devices to perform the various steps.

Having described my invention, what I claim and desire to secure by Letters Patent is:—

1. In a device of the character described, the combination of a conveyer, a match 35 plate upon the conveyer, said match plate being provided with a pattern, a flask comprising hinged cope and drag sections which rest upon the match plate, means for filling the flask sections with sand and tamping the same in position, means for inverting the flask sections upon the conveyer, means for removing the match plate, and means for swinging one flask section over upon the opposite flask section.

2. In a device of the character described, the combination of a conveyer, a match plate upon the conveyer, said match plate being provided with a pattern, a flask comprising complementary sections which rest upon the 50 match plate, means for filling the flask sections with sand and tamping the same in position, means for inverting the flask sections upon the conveyer and removing the match plate therefrom, and means for bringing the two complementary flask sections together into operative position.

3. In a device of the character described, the combination of a conveyer, a match plate upon the conveyer, a flask comprising complementary sections which rest upon the match plate, means for filling the flask sections with sand and tamping the same in position therein, a swinging reversing frame provided with a pocket arranged in the path 60 of the flask sections and match plate to re-

ceive the same, said reversing frame lifting the flask sections and match plate from the conveyer and again depositing them upon the conveyer in an inverted position, means for removing the match plate, and means for bringing the flask sections together in operative relation.

4. In a device of the character described, the combination of a conveyer, a match plate upon the conveyer, said match plate 70 being provided with a pattern, a flask comprising hinged cope and drag sections which rest upon the match plate, means for filling the flask sections with sand and tamping the same in position therein, a swing 75 ing reversing frame provided with a pocket arranged in the path of the flask sections and match plate to receive the same, said reversing frame serving to lift the flask sections and match plate from the conveyer 80 and again deposit the same upon the conveyer in an inverted position, means for removing the match plate from the flask sections, and cam actuated means for automatically swinging one flask section over upon the opposite 85 flask section.

5. In a device of the character described, the combination of a conveyer, a match plate upon the conveyer, said match plate being 90 provided with a pattern, a flask comprising hinged cope and drag sections which rest upon the match plate, means for filling the flask sections with sand and tamping the same in position therein, means for inverting the flask sections upon the conveyer, means 95 for removing the match plate from the flask sections, a guide member projecting from one of the flask sections, and a cam surface arranged in the path of the said guide member for coöperation therewith to swing one 100 of the flask sections over upon the opposite flask section.

6. In a device of the character described, the combination of a conveyer, a match plate resting upon the conveyer and provided with 110 a pattern, a flask comprising hinged cope and drag sections which rest upon the match plate, means for filling the flask sections with sand and tamping the same in position therein, means for inverting the flask sections upon the conveyer, means for removing the match plate therefrom, a guide member projecting from one of the flask sections, a double inclined cam surface arranged in the path of the guide member, and a trigger 115 at the apex of the double inclined cam surface, the said double inclined cam surface and trigger coöperating with the guide member to automatically swing one of the flask sections over upon the opposite flask section.

7. A device of the character described, including a conveyer, a flask carried by the conveyer and comprising hinged sections, a guide member projecting from one of the flask sections, and a cam surface arranged 120

in the path of the guide member for automatically swinging the said flask section over upon the opposite flask section.

8. In a device of the character described, 5 the combination of a conveyer, a flask mounted upon the conveyer and comprising a pair of hinged complemental sections, a guide member projecting from one of the flask sections, a double inclined cam surface 10 arranged in the path of the guide member, and switch means at the apex of the double inclined surface for coöperation with the double inclined surface and guide member upon the flask section for swinging the said 15 flask section over upon the opposite flask section.

9. A device of the character described including a conveyer, a flask mounted upon the conveyer and comprising a pair of 20 hinged sections, a guide member projecting from one of the flask sections, a double inclined surface arranged in the path of the guide member, a vertical guideway over the apex of the double inclined surface, a swinging 25 trigger at the apex of the double inclined surface for directing the guide member between the vertical guideway and the opposite sides of the double inclined surface, said double inclined surface and swinging trigger 30 serving to coöperate with the guide

member upon the flask section to automatically swing the said flask section over upon the opposite flask section.

10. In a device of the character described, the combination of a conveyer, a series of 35 flasks upon the conveyer, each of the flasks comprising hingedly connected drag and cope sections, a match plate for each of the flasks, said match plates carrying patterns and having the respective flasks placed thereon, means for charging the flasks with sand as they are advanced by the conveyer, means for tamping the same within the flasks, reversing mechanism adapted to successively act upon the flasks to invert the same upon 40 the conveyer, a stripping device adapted to act successively upon the flasks to remove the match plates and patterns therefrom, and a device comprising an incline and co-operating guide to swing the cope sections 45 of the flasks upon the drag sections of the flasks, substantially as set forth.

In testimony whereof, I have hereunto signed my name in the presence of two subscribing witnesses.

CHARLES G. ROBINSON.
